HOOD CATCH

Arthur Claud-Mantle, Trumbull, Conn., assignor
to The Bassick Company, Bridgeport, Conn., a
corporation of Connecticut

Application October 1, 1934, Serial No. 746,285

2 Claims. (Cl. 292—228)

The present invention relates to hood catches for securing the hoods of automobiles, and has for an object to provide a hood catch which will effectually hold the hood downwardly and inwardly against looseness and rattling. Another object is to provide a hood catch in which the handle means will be exteriorly disposed and in which the spring actuated lever arm and operating parts of the catch will be interiorly disposed, so that only the handle need have a highly or expensively finished surface. A further object is to provide a hood catch in which the parts will be arranged in generally horizontal direction out of relation with the sill, thus providing a catch which may be easily and positively operated, and which at the same time will present a neat and inconspicuous appearance, free from unsightly mechanism, and which lends itself to streamline design, harmonizing with other parts of the automobile structure.

A further object is to provide a catch in which the spring means will be mounted on the lever in proximity to the keeper and will be so arranged that the manual pressure required to tension it in engaging and disengaging the catch will be relatively light.

Another object is to provide a mounting element for the catch which may be used either for right or left catches, and further to provide a construction in which the lever and mounting element may be conveniently formed of sheet metal, to the end that a strong, efficient, compact and inexpensive structure is produced.

A still further object is to provide a hood catch which will utilize the springiness or inherent resiliency of the metal of the hood side to exert inward holding pressure.

With the above and other objects in view an embodiment of the invention is shown in the accompanying drawing, and this embodiment will be hereinafter more fully described with reference thereto, and the invention will be finally pointed out in the claims.

In the drawing:

Fig. 1 is a front elevation of one corner of an automobile hood and the adjoining cowl and sill structure, and showing the hood catch, according to an exemplary embodiment of the invention, attached thereto.

Fig. 2 is a horizontal sectional view, taken along the line 2—2 of Fig. 1.

Fig. 3 is a vertical sectional view, taken along the line 3—3 of Fig. 1.

Fig. 4 is an inside elevation of the catch.

Fig. 5 is a vertical sectional view, taken along the line 5—5 of Fig. 4.

Fig. 6 is a diagrammatic horizontal sectional view of the hood, partially broken away, and showing somewhat exaggerated the flexing of the hood in the operative position of the catches at each end.

Similar reference characters indicate corresponding parts throughout the several figures of the drawing.

Referring to the drawing, the hood 10 is adapted to close against the inset marginal edge portions 11—11 of the radiator frame and cowl structure 12—12, and at each end of the hood, and adapted to cooperate with keepers provided on the radiator frame and cowl structures, hood catches, according to the illustrated embodiment of the invention, are mounted.

The hood catch comprises a mounting member formed of sheet metal and consisting of a marginal flange or base portion 13 secured by rivets 14 to the inner side of the hood, a raised pivot mounting portion 15, a retaining strap portion 16 disposed forwardly of and outwardly offset from the pivot mounting portion 15, and a pair of inwardly projecting spaced ears 17—17 forwardly of and inwardly offset from the retaining strap portion 16.

The hood catch lever 18, preferably formed of sheet metal and having longitudinal reinforcing ribs 19—19 formed therein, is pivotally mounted at its end upon the pivot mounting portion 15 by means of a pivot stud 20 and extends beneath the retaining strap portion 16 and above the ears 17—17, being provided forwardly of the ears and at its under side with a coil spring 21 secured thereto by a U-shape clip 22 engaged over the inner end of the spring and having its ends engaged through slots 23—23 in the lever and secured by bending over these ends. The outer curved end of the spring extends between the ears 17—17 and hooks upon the lower one.

The inner surfaces of the side walls of the retaining strap portion 16 diverge and constitute limiting stops to limit the swing of the lever 18, being respectively substantially parallel to the upper and lower edges of the lever in the respective upper position of the lever, when the same is disengaged from the keeper and pressed upwardly by the spring, and in the lower position when it is manually pressed downwardly against the pressure of the spring.

The outer end portion of the lever 18 is bent toward the hood, as at 24, and at its extremity is bent at right angles, as at 25, to provide a keeper 55.

engaging portion, this portion 25 being provided for this purpose with an upwardly extending lug 26 having a slightly inclined forward edge.

An exterior handle member 27, having a shank portion 28 extending through an arcuate slot 29 in the hood, is rigidly secured to the portion 24 of the lever, the end of the shank being flattened, as at 30-30, and screw-threaded, and engaged through a correspondingly shaped aperture 31 in the portion 24, to which it is secured by a nut 32 screwed upon the threaded shank.

While any suitable type of keeper may be provided, I have shown the same as a right angularly bent downwardly disposed bar 33 secured 15 to the inset abutment flange 11 by means of rivets 34-34, the abutment flange being cut away, as at 35, to provide an entrance passage for the end of the catch lever.

In operation, the hood is drawn downwardly 20 by downward pressure on the catch handles 27 at each end of the hood, the abutment of the lower edge of the catch levers 18 with the lower walls of the strap portions 16 causing the downward pressure of the levers to be firmly transmitted to the hood, so that it is effectually pulled 25 down to its full limit with facility. When fully pulled down the hood is pressed inwardly disposing the lugs 26 of the levers 18 inwardly of the keepers, so that upon release the levers spring 30 upwardly under the pressure of the spring 21 and engage the lugs behind the keepers, thus retaining the hood closed and exerting downward pressure thereon.

The levers 18 are transversely rigid with respect 35 to the mounting member, which in turn is rigid with the hood, and the relation of the keepers to the plane of the hood is such that the levers must be forcibly pressed inwardly to engage the lugs 26 therewith. The ends of the hood being supported 40 against the radiator and cowl abutments 11-11, the inward pressure of the levers through the transversely rigid connection with the hood, causes the hood to be slightly sprung or warped, as indicated diagrammatically in Fig. 6, being 45 held in this position by the inherent springiness of the hood and exerting such pressure upon the hood that the hood ends are firmly pressed inwardly against the abutments 11-11.

To disengage the catch from its keeper the 50 handle 27 is simply pressed downwardly and the hood swung outwardly, the spring 21 moving the lever to its inoperative position against the upper wall of the strap portion 16.

I have illustrated and described a preferred 55 and satisfactory embodiment of the invention, but it will be obvious that changes may be made therein, within the spirit and scope thereof, as defined in the appended claims.

Having thus described my invention what I 60 claim and desire to secure by Letters Patent is:-

1. Automobile hood fastening means for engaging a keeper disposed upon a fixed part in relation to the end of the hood, comprising a mounting fixture adapted to be secured to the interior of the hood, a catch lever pivotally mounted at one end upon said mounting fixture upon a portion of said fixture underlying said lever, said lever having a keeper engaging portion

at the other end, said mounting fixture having a movement limiting bridging portion between the pivotal mounting of said lever and the keeper engaging portion having a transverse portion and side walls, said transverse portion being disposed 5 at the side of said lever opposed to the hood side, whereby said lever is substantially rigidly supported thereby with respect to the pivotal axis against inward pressure on the keeper engaging end of said lever, the side walls of said bridging portion constituting movement limiting stops for limiting the swing of said lever about said axis, spring means cooperating between said catch lever and said mounting fixture and exerting upward pressure on said catch lever, and a handle 15 secured to said catch lever between said bridging portion and said keeper engaging portion extending to the exterior of the hood, said catch lever adapted to be depressed in closing the hood to pull the hood downwardly and to spring upwardly to engage said keeper under the pressure of said spring means, the effective spring movement of said catch lever being from a point below its point of engagement with the keeper to a point above said point of engagement whereby a 25 continuous downward pressure is exerted on the hood.

2. Automobile hood fastening means for engaging a keeper disposed upon a fixed part in relation to the end of the hood, the hood in its 30 closed position being limited in its inward movement by engagement of its end portions with a fixed part, comprising a mounting fixture adapted to be mounted upon the interior of the hood at one end in longitudinally spaced relation to 35 the point of engagement of said hood with said fixed part, and said hood being inherently resilient, a catch lever pivotally mounted at one end upon said mounting fixture for rotation about an axis normally perpendicular to the hood surface 40 and having a keeper engaging portion at its other end, said mounting fixture having a movement limiting portion between the pivotal mounting of said lever and the keeper engaging portion disposed at one side of said lever whereby said lever is substantially rigidly supported thereby with 45 respect to said axis, spring means cooperating between said mounting fixture and said catch lever and adapted to press said catch lever upwardly into engagement with said keeper, a 50 handle secured to said catch lever between said mounting fixture and said keeper engaging portion and extending to the exterior of the hood, said catch means being movable in generally parallel relation to the normal plane of the hood, and said keeper engaging portion being normally 55 transversely outwardly of its keeper engaging position, and being further movable by inward pressure in a transverse direction to the normal plane of the hood to engage said keeper, the engagement of said catch with said keeper adapted through said rigid support of said mounting fixture to warp the hood between its ends, whereby the inherent resiliency of the hood sets up pressure to press its ends inwardly against said fixed 60 part.

ARTHUR CLAUD-MANTLE.
